UNITED STATES PATENT OFFICE.

FRANK WEBB, OF READING, MASSACHUSETTS.

STAY FOR PNEUMATIC MATTRESSES, &c.

SPECIFICATION forming part of Letters Patent No. 787,137, dated April 11, 1905.

Application filed September 12, 1904. Serial No. 224,092.

To all whom it may concern:

Be it known that I, FRANK WEBB, of Reading, in the county of Middlesex and State of Massachusetts, have invented certain new and 5 useful Improvements in Stays for Pneumatic Mattresses, &c., of which the following is a specification.

This invention relates to stays which are used to connect the opposite side pieces of 10 pneumatic mattresses and other inflatable sacks to limit the separation of said side pieces by the pressure of the air. Stays of this character usually embody a main or body portion which extends between the two side pieces 15 and flaps or ears at the ends of the body portion, said flaps being suitably secured to the side pieces. To give the stays suitable flexibility, they are usually made of flat strips of 20 fabric, the end portions of which are cut lengthwise to form two flaps or ears at each 25 end of the stay, said flaps being bent outwardly from opposite sides of the stay and secured to the side pieces of the mattress. Heretofore flat stays for this purpose have 30 been lacking in strength and durability at the points where the flaps are bent outwardly from the body of the stay, the construction heretofore used having been such that there is liability of the tearing of the material of the

stay at these points.

My invention has for its object to provide a flat stay of textile fabric which shall be free from the objections above noted; and to this end the invention consists in the improvements which I will now proceed to describe and claim.

Of the accompanying drawings, Figure 1 represents an edge view of a strip of textile fabric prepared for the manufacture of my 40 improved stay. Fig. 2 represents a perspective view of a stay embodying my invention made from the strip shown in Fig. 1. Fig. 3 represents a view similar to Fig. 2, showing the central portion of the stay formed in two 45 plies to increase its flexibility. Fig. 4 represents a sectional view showing one of the end portions of the stay attached to one of the side pieces of a mattress.

The same reference characters indicate the same parts in all the figures.

In carrying out my invention I produce a strip of woven fabric which includes a series of body portions a of maximum thickness and a series of intermediate portions which comprise two plies a' , each of the same width as the body portion a and of half its thickness. The said strip may be woven by any suitable means or processes known to those skilled in the art of weaving, the parts a and a' being integral with each other and provided with 55 selvage edges, so that there are no raw edges or such edges as would be formed by cutting the fabric. The two-ply portions of the strip thus formed are severed on the lines b , the operation of severing the strip converting the 60 plies a' into ears adapted to be bent outwardly from the body a of the strip, as shown in Fig. 2, each ear being of the same width as the body of the strip and of practically half its thickness. The stay thus formed may 65 be attached to the side pieces d of a mattress by inserting the strip through an orifice d' , placing the ears a' upon the outer surface of the side piece d , and securing said ears in place by means of a covering-piece e , which is prepared to be secured to the flaps a' and to the 70 side piece d by the vulcanization of rubber which is incorporated into said parts.

It will be seen that the flaps a' are integral with the body a and free from raw edges at 75 the points where they join the body. The bases of the flaps are intimately united with the body of the strip by the weaving operation, so there is no possibility of the said bases being torn apart without breaking the threads 80 of which the fabric is composed.

To increase the flexibility of the stay, the central part of the body portion may be woven in two plies a'' , as shown in Fig. 3.

I claim—

1. A stay for the purpose specified, comprising a strip of woven fabric divided at its end portions to form flaps or flanges which are integral with the body of the strip and are of the same width as said body and of substantially half its thickness, the said flaps being 95

adapted to be bent outwardly from opposite sides of the body of the strip.

2. A stay for the purpose specified, comprising a strip of woven fabric divided at its 5 end portions to form flaps or flanges which are integral with the body of the strip and are of the same width as said body and of substantially half its thickness, the said flaps being adapted to be bent outwardly from opposite

sides of the body of the strip, said strip being made in two parts or plies at an intermediate portion to increase the flexibility of the strip.

In testimony whereof I have affixed my signature in presence of two witnesses.

FRANK WEBB.
